UNITED STATES PATENT OFFICE.

RAYMOND B. PRICE, OF NEW YORK, N. Y., ASSIGNOR TO RUBBER REGENERATING COMPANY, A CORPORATION OF INDIANA.

RUBBER ARTICLE AND PROCESS OF MAKING SAME.

1,199,922.

Specification of Letters Patent.

Patented Oct. 3, 1916.

No Drawing.

Application filed December 29, 1914. Serial No. 879,590.

To all whom it may concern:

Be it known that I, RAYMOND B. PRICE, a citizen of the United States, residing in the city of New York, county and State of New York, have invented certain new and useful Improvements in Rubber Articles and Processes of Making Same, of which the following is a full, clear, and exact disclosure.

10 This invention relates to the manufacture of rubber articles.

It has been found that the arrangement of straight fibers bound together with a vulcanizable plastic binder in textile work, produces a somewhat stiff product, for instance, when several layers of straight fibers, thread, strands, cords, or the like, are placed in the wall of a tire, a truss action results and the wall is too stiff, and it is such inelasticities in rubber and fabric articles that my present invention overcomes.

As far as I am aware, every plan of making automobile tires, hose and rubber goods generally, involves the use of rubber treated straight fibers, twisted into threads, strands, or cords, and used in such form, or woven, braided or knitted into fabric. These straight fibers are non-extensible longitudinally, consequently, cannot yield under the longitudinal stress. To obviate this defect, I contemplate the use of non-straight elements such as fibers, threads, cords and the like, united with rubber, or rubber-like material, whereby longitudinal yielding of the same may occur under stress.

15 The invention in its broadest aspect contemplates the embodiment of vulcanizable plastic treated elements, having an inherent wave of outline in textile work. The contour of such element may be controlled along predetermined lines or not, as is desired, according to the use to which the article is to be put. Furthermore, as vulcanization is to be considered in connection with the ultimate product, I contemplate partial or whole vulcanization at any stage in the manufacture, which would require such treatment to be practical.

20 When in this application I use the term "inherent", it is intended to include any irregularity of outline, such as crimps, corrugations and the like, other than that imparted to the element in building it into the article, and when I use the term "vulcanizable plastic", it is intended to include

not only rubber, but also gutta percha, bala-
lata, and the like, which although not com-
monly vulcanized, are in fact capable of vul-
canization or setting.

More specifically, the invention consists 60
in effecting controlled irregularities in such
elements as fibers, threads, strands, cords,
and the like, treating the same with a vul-
canizable plastic, assembling a plurality of
such elements to form elements of larger di- 65
mension and partially or wholly vulcanizing
the same, whereby the resulting product
embodies inherently irregular fibrous ele-
ments united with rubber or rubber-like ma-
terial in a homogeneous unitary body which 70
can yield in the direction of the length of
said elements under stress.

In carrying out my invention, there are
a wide number of variations possible in the
sequence of manipulation of the fibrous ele- 75
ments and vulcanizable plastic, and my in-
vention is not limited to any particular se-
quence which will hereafter be described,
but is intended to include all and every se-
quence which attains the results and condi- 80
tions which the principle involved in my
invention produces in textile and rubber
work.

In an embodiment of my invention, the
fibrous elements, such as fibers, strands, 85
threads, cords, or the like, are distorted out
of the straight, treated with a vulcanizable
plastic, assembled to form elements of larger
dimension, and partially or wholly vulcan- 90
ized. The distortion may be performed si-
multaneously with the treating, assembling
and vulcanizing steps, or independently
therefrom, or any sequence of the steps may
be utilized, it being only necessary to the 95
practice of my invention, that in the final
product or article of manufacture, there ap-
pear fibrous elements having an irregularity
of outline other than that imparted to them
in the building of the article.

A few of the many possible variations in 100
sequence of manipulation will now be enum-
erated by way of example. I contem-
plate disposing a layer of parallel fibers in
a corrugated mold, together with a vulcan-
izable plastic, and thereby crimping the fi- 105
ber and plastic simultaneously, either with
or without vulcanization. A somewhat simi-
lar result could be obtained by passing them
through corrugated rolls. I contemplate
crimping fibers, then twisting, weaving, 110

braiding, or otherwise building the crimped fibers into elements of larger dimension and then applying a vulcanizable plastic thereto. I contemplate applying a vulcanizable plastic to straight fibers, then crimping the product, and then twisting, weaving, braiding, or otherwise building the same into elements of larger dimension. I contemplate partial or whole vulcanization at any step in the manufacture that would require such treatment to be practical, or find it of advantage. Furthermore, although in the above examples, I have in each instance enumerated fibers, I desire it to be understood that the words "strand", "thread", or "cord" may be substituted for the word "fibers", and the example read accordingly.

From the above description it can now readily be seen that the principle involved 20 in my invention resides in producing certain advantageous conditions and results in textile and rubber articles of manufacture, which include yielding in the direction of the length of the fibrous elements thereof, together with greater efficiency in load supporting qualities, and these results or conditions I produce by the embodiment in such articles of inherently irregular fibrous elements.

Having described my invention, what I claim and desire to protect by Letters Patent is:

1. The process of manufacturing material consisting of crimping fibrous elements, 35 treating the same with a vulcanizable plastic, assembling a plurality of such elements with the crimps unconfined and free to straighten out to form elements of larger dimension extensible in the direction of length 40 of the crimped elements, and partially or wholly vulcanizing the same.
2. The process of manufacturing material consisting of crimping and coating fibrous elements with a vulcanizable plastic, assembling a plurality of such elements with the

crimps unconfined and free to straighten out to form elements of larger dimension extensible in the direction of length of the crimped elements, and vulcanizing the same.

3. The process of manufacturing material 50 consisting of crimping fibrous elements, treating the same with a vulcanizable plastic, twisting a plurality of such elements with the crimps unconfined and free to straighten out to form elements of larger dimension extensible in the direction of length 55 of the crimped elements, and vulcanizing the same.

4. The process of manufacturing material 60 consisting of crimping fibrous elements, treating the same with a vulcanizable plastic, weaving a plurality of the same with the crimps unconfined and free to straighten out into elements of larger dimension extensible in the direction of length 65 of the crimped elements and vulcanizing the same.

5. An article of manufacture embodying inherently irregular fibrous elements extensible longitudinally of their lengths, united 70 with a vulcanizable plastic.

6. An article of manufacture embodying inherently irregular fibrous elements extensible longitudinally of their lengths and rubber, or rubber-like material, united in a 75 homogeneous unitary body.

7. An article of manufacture embodying vulcanizable plastic treated fibrous elements having an irregularity of outline other than that imparted to them in the building of the article, extensible longitudinally of their 80 lengths by the straightening out of the irregularity of the outline thereof under stress.

Signed at New York, N. Y., December 28, 1914.

RAYMOND B. PRICE.
